[57] CLAIM

The ornamental design of a bean bag camera support, as
shown and described.

DESCRIPTION

FIG. 1 is a top plan view of a bean bag camera support
showing my new design;

FIG. 2 is a bottom plan view thereof;

FIG. 3 is a side elevational view thereof;

FIG. 4 is a side elevational view as seen from the side
opposite FIG. 3;

FIG. 5 is an end elevational view thereof; and

FIG. 6 is an end elevational view as seen from the end
opposite FIG. 5.
